ELECTRIC MOTOR CONTROL SYSTEM

Ralph G. Lockett, Wauwatosa, Wis., assignor to
Cutler-Hammer, Inc., Milwaukee, Wis., a cor-
poration of Delaware

Application March 4, 1935, Serial No. 9,139

17 Claims. (Cl. 172—240)

This invention relates to improvements in electric motor control systems. The invention is particularly applicable to reversing and acceleration control of the driving motor of a rotary washing machine or the like.

A primary object of the invention is to provide an improved and simplified system of control for direct current driving motors of washing machines and the like.

10 Another object is to provide novel means for insuring proper protection to the driving motor during starting while minimizing the time required for effecting acceleration thereof in each instance.

15 Another object is to minimize the cost of a control system having the characteristics aforementioned.

Another object is to provide a novel form of control drum for use in a system of the character aforementioned.

Another object is to provide a simple form of manually operable means for initiating or interrupting operation of the control system.

Another object is to provide a novel combination of elements including a continuously rotatable drum for automatically effecting operation of the electromagnetically operable reversing and accelerating switches in a predetermined order.

Other objects and advantages of the invention 30 will hereinafter appear.

In the drawing,

Figure 1 illustrates schematically and diagrammatically an electric motor control system as constructed in accordance with my invention, it being understood that the embodiment illustrated is susceptible of modification as to certain details of construction thereof without departing from the scope of the appended claims, and

Fig. 2 is a fragmentary view showing a modified 40 form of control drum for use in a system of the character illustrated in Fig. 1.

Referring first to Fig. 1, the numeral 5 designates in general a washing machine of well known form. Said machine as shown comprises 45 an outer tub or casing 6 within which is mounted a rotatable cylinder designated by the numeral 7. Cylinder 7 may be of the single compartment type having a single door to be registered with the opening provided in tub 6, said tub 50 having a door 8 to provide for closure of said opening. Cylinder 7 may, of course, be of the type provided with two, three or more radial compartments,—each compartment being provided with a door to be brought into register 55 with the opening in tub 6. Also it is to be under-

stood that the washer 5 may be of considerably greater horizontal length, and that the cylinder may be provided with any desired number of suitably spaced vertical walls or partitions to afford the desired number of washer compartments,—the tub, of course, being provided with a corresponding number of openings and doors to afford proper access to said compartments.

5 Cylinder 7 is connected by shaft 9, reduction gearing 10, and shaft 11 with the armature of a 10 motor M to be driven by the latter. The series field of motor M is designated by the numeral 12, and the shunt field thereof is designated by the numeral 13,—the latter having connected in parallel therewith a well known form of field discharge resistance 14. A pair of resistances 15 and 16 is provided, and the control means now to be described are adapted to insure initial inclusion of said resistances in circuit in series with the motor armature each time the motor circuit is completed for operation thereof in one 15 direction or the other, and to thereafter insure exclusion of said resistance sections in sequence within a predetermined relatively short period of time. In this manner I insure proper 20 protection for the motor in each instance during starting thereof, while providing for full acceleration thereof within a predetermined minimum period of time.

The control means for motor M comprises a 30 pair of normally open electromagnetically operable reversing switches 17 and 18, a pair of normally open electromagnetically operable accelerating switches 19 and 20, and a control drum designated in general by the reference character D. 35 Switch 17 is provided with normally open main contacts 21 and 22, normally open auxiliary contacts 23 and an operating winding 24. Switch 18 is provided with normally open main contacts 25 and 26, normally open auxiliary contacts 27, and an operating winding 28. Switch 19 is provided with normally open main contacts 29, normally open auxiliary contacts 30, and an operating winding 31. Switch 20 is provided with normally open contacts 32, and an operating 40 winding 33.

45 Stationary contacts 34 to 39, inclusive, are provided for cooperative engagement by the segments carried by drum D. The development of drum D is illustrated in the drawing,—it being 50 understood that in practice the left-hand and right-hand edges thereof will be united or connected to provide a drum of cylindrical form. As shown, all of the segments carried by drum D are electrically connected with each other,—the 55

segments at the left-hand side of the vertical center line of the drum being adapted to cooperate with contacts 34, 35, 36, 38, and 39 to control operation of motor M in one (say, the forward) direction, and the segments at the right-hand side of said vertical center line being adapted to cooperate with contacts 34, 35, 37, 38, and 39 to control operation of motor M in the reverse direction.

10 The left-hand side of drum D is provided with a pair of relatively long segments 40 and 41 of substantially equal dimensions, said segments being vertically spaced from and aligned with each other,—the same being adapted for cooperative engagement with contacts 34 and 35 as herein-after described. Positioned beneath the segments 40 and 41 and arranged within the circumferential limits of the latter is a group of five relatively small or short segments 42 to 46, inclusive, which are equally spaced from each other, and adapted for cooperative engagement with contact 36. Engagement of any one of the segments 42 to 46, inclusive, with contact 36 is adapted to provide for energization and closure of switch 17, assuming prior closure of a manually operable switch 52 by closure of tub door 8.

Also positioned beneath segments 40 and 41 and arranged within the circumferential limits of the latter is a second group of five relatively small segments 47 to 51, inclusive, which are equally spaced from each other, and adapted for cooperative engagement with contact 38. Engagement of any one of the segments 47 to 51, inclusive, with contact 38 is adapted to provide for energization and closure of accelerating switch 19,—but subject to prior closure of the normally open auxiliary contacts of switch 17. In this connection it is to be noted that segments 47 to 51 are arranged in individually offset and non-overlapping relationship circumferentially of the drum with reference to the respective segments 42 to 46, wherefore a relatively short but predetermined period of time is required to lapse between closing energization of switch 17 and closing energization of switch 19.

Also positioned beneath segments 40 and 41 and arranged within the circumferential limits of the latter is a third group of relatively small segments 53 to 56, inclusive, which are equally spaced from each other, and adapted for cooperative engagement with contact 39. Engagement of any one of the segments 53 to 56, inclusive, with contact 39 is adapted to provide for energization and closure of accelerating switch 20,—but subject to prior closure of the normally open auxiliary contacts 30 of switch 18. In this connection it is to be noted that segments 53 to 56 are arranged in individually offset and non-overlapping relationship circumferentially of the drum with reference to the respective segments 47 to 50, wherefore a relatively short but predetermined period of time is required to lapse between closing energization of switch 18 and closing energization of switch 20.

65 The right-hand side of drum D is provided with a pair of segments 57 and 58 identical with the segments 40 and 41, but endwise spaced from and aligned with the latter respectively. Offset downwardly from segments 57 and 58 and located within the circumferential limits of the latter is a group of five relatively small equally spaced segments 59 to 63, inclusive, which are adapted for cooperative engagement with contact 37 to provide for closing energization of the winding 28 of reversing switch 18 in the manner hereinafter

described. Offset downwardly from and individually offset circumferentially with respect to segments 59 to 63 is a group of five relatively small segments 64 to 68 which are circumferentially aligned with segments 47 to 51, and likewise adapted for cooperative engagement with contact 38 to provide for closing energization of the winding 31 of accelerating switch 19, but subject to prior closure of the auxiliary contacts 27 of switch 18, as hereinafter described. Offset downwardly from and individually offset circumferentially with respect to segments 64 to 67 is a group of four relatively small segments 69 to 72,—the latter being circumferentially aligned with segments 53 to 56, and likewise adapted for cooperative engagement with contact 39 to provide for closing energization of the winding 33 of accelerating switch 20, but subject to prior closure of the auxiliary contacts 30 of switch 19, as hereinafter described.

As will be apparent, the right-hand and left-hand sides of drum D contain like numbers of segments similarly arranged, with the exception that segments 42 to 46 are adapted for engagement with contact 36, whereas segments 59 to 63 are arranged for engagement with contact 37. While I have diagrammatically shown all of the segments on drum D as electrically connected with each other by suitable wiring, it is to be understood that this result may likewise be attained by forming the drum D of conducting material, such as metal, and directly electrically connecting the various segments thereto in any well known manner. For instance, the relatively small segments 42 to 51 and 53 to 56 and 59 to 68 may comprise the square heads of bolts the shanks of which have threaded engagement with the drum cylinder.

Drum D is adapted to be continuously driven unidirectionally (as indicated by the arrow) by a 40 pilot motor 73 which is connected across the direct current supply lines L¹, L² as by means of conductors 14 and 15. A manually operable switch 76 may be employed if desired to provide for disconnection of motor 73 from the source of energy supply. I also preferably employ a manually operable switch, shown diagrammatically at 77 and 78, to provide for disconnection of the entire control system from the source of energy supply L¹, L².

The control system aforescribed further comprises a plurality of interlocking or current-limiting resistances 79, 80, 81 and 82, which are interposed between the drum contact 35 and the windings 24, 28, 31, and 33 of switches 17, 18, 19, 20, respectively, whereby upon engagement of segment 41 or segment 58 with contact 35 said windings will be energized to a degree only sufficient to hold the respective switches closed after full energization of the respective windings thereof, whereas the drum contacts 36 to 39 and the segments associated therewith cooperate in the manner hereinafter described to effect short-circuiting of the resistances 79 to 82 in a predetermined sequence to provide for proper reversing and acceleration control of motor M.

Assuming positioning of the several parts as illustrated, and further assuming closure of switch contacts 76, 77, 78 the operation of the aforescribed control system is as follows. Upon closure of the switch contacts 52 by closure of tub door 8, with drum D in one of its two "off" positions, as illustrated, it is apparent that upon engagement of segments 40 and 41 with contacts 34 and 35, the various windings 24, 28, 31, 33

and 33 will be energized, but not to a sufficient degree to effect closure of their respective switches, due to inclusion in the several circuits of the resistances 79 to 82. However, the short 5 segment 42 of drum D will simultaneously engage contact 36, thereby completing an energizing circuit for the winding 24 of switch 17, which circuit extends from line L¹ by conductor 83 through contacts 52 of the tub door switch, conductor 84 to contact 34, through segments 40 and 42 to contact 36, conductor 85 through said winding 24, and by conductors 86, 87 and 88 to line L².

The main contacts 21 and 22 of switch 17 are thus closed to complete an energizing circuit for 15 motor M, which circuit may be traced from line L¹ by conductor 89 through contacts 21 and downwardly through the motor armature, thence through contacts 22, resistance sections 15, 16 and series field 12 to line L², whereby motor M 20 is started in one direction at slow speed. Moreover, due to engagement of segment 41 with contact 35 the winding 24 will be maintained energized to a sufficient degree to hold switch 17 closed pending disengagement of segment 41 from 25 contact 35 by continued rotation of drum D.

The auxiliary contacts 23 of switch 17 when closed are adapted to preset a circuit for closing energization of the winding 31 of accelerating switch 19 upon engagement of segment 47 with 30 contact 38. As aforementioned, segment 47 is arranged in circumferentially offset and non-overlapping relationship to segment 42, thus requiring lapse of a short but predetermined period of time between closing of switch 17 and closing 35 energization of the winding 31 of switch 19. Thus upon engagement of segment 47 with contact 38 the winding 31 is energized by a circuit extending from line L¹ to contact 34, as aforementioned, thence through segments 40 and 41 40 to contact 38, by conductor 90 through said winding 31, conductor 91 through auxiliary contacts 23 of switch 17, and by conductors 92, 86, 81, and 88 to line L². Thereafter winding 31 will be sufficiently energized, by a circuit extending 45 through resistance 81, to hold switch 19 closed pending disengagement of segment 41 from contact 35.

The main contacts 29 of switch 18 when closed are adapted to exclude resistance section 15 from 50 the armature circuit of motor M by a shunt connection extending through said contacts. The auxiliary contacts 30 of switch 18 when closed are adapted to preset a circuit for closing energization of the winding 33 of switch 20 upon 55 engagement of segment 53 with contact 39. Said circuit may be traced from line L¹ to contact 34, thence through segments 40 and 53 to contact 39, by conductor 93 through said auxiliary contacts 30 and said winding 33, thence by conductor 94, auxiliary contacts 23, and conductors 92, 86, 87, and 88 to line L². As aforementioned segment 53 is arranged in circumferentially offset and non-overlapping relationship to segment 47 60 to insure against closure of switch 20 pending lapse of a short but predetermined period of time after closure of switch 18. Upon closure of the contacts 32 of switch 20 resistance 16 is excluded by a connection shunting both of the resistances 15 and 16, whereby the armature of 65 motor M is connected directly across lines L¹, L² for full speed operation thereof. Thereafter winding 33 will be sufficiently energized, by a circuit extending through contact 34, segments 40 and 41, contact 35 and resistance 82, to hold 70

switch 20 closed pending disengagement of segment 41 from contact 35.

Due to continued rotation of drum D segments 40 and 41 will eventually be disengaged from contacts 34 and 35, and all other segments at 5 the left-hand side of the drum will likewise be disengaged from their cooperating contacts, with the result that complete de-energization of the operating windings of the aforementioned switches 17, 19, and 20 is insured, to interrupt 10 the energizing circuit of the armature of motor M. Within a relatively short predetermined period of time thereafter the segments 57, 58, and 59 at the right-hand side of drum D will simultaneously engage contacts 34, 35, and 37, thereby 15 completing a circuit for closing energization of the winding 28 of reversing switch 18. Said circuit may be traced from line L¹ to contact 34, in the manner aforementioned, thence through segments 57 and 59 to contact 37, by conductor 20 94 through said winding 28, and by conductors 87 and 88 to line L².

The main contacts 25 and 26 when closed complete a circuit for the armature of motor M, said circuit extending from line L¹ by conductor 25 95 through contacts 26, by conductor 96 upwardly through said armature, thence through contacts 25, and by conductor 97 through resistances 15, 16 and series field 12 to line L². Thereafter drum D acts through segment 58, contact 30 35 and current-limiting resistance 80 to provide a sufficient degree of energization of winding 28 to maintain switch 18 closed pending disengagement of segment 58 from segment 35.

The auxiliary contacts 27 of switch 18 when closed are adapted to preset a circuit for closing energization of the winding 31 of switch 19 upon engagement of segment 64 with contact 38, said circuit extending from line L¹ to contact 34, thence through segments 57 and 64 to contact 38, by conductor 90 through said winding 31, by conductor 91 through said contacts 27, and by conductor 88 to line L². As will be noted, segment 64 is arranged in circumferentially offset and nonoverlapping relationship to segment 59, thus requiring 45 lapse of a short but predetermined period of time between closing of switch 18 and closing energization of the winding 31 of switch 19. After switch 19 is closed the winding 31 will be energized sufficiently to maintain the same closed through the 50 medium of resistance 81, pending disengagement of segment 58 from contact 35.

The main contacts 29 of switch 19 when closed act in the manner aforementioned to effect exclusion of resistance section 15 from the armature 55 circuit of motor M. The auxiliary contacts 30 of switch 19 when closed are adapted to preset a circuit for closing energization of the winding 33 of switch 20 upon engagement of segment 69 with contact 39. Said circuit may be traced from line 60 L¹ to contact 34, thence through segments 57 and 69 to contact 39, by conductor 93 through said auxiliary contacts 30 and said winding 33, thence by conductor 94, auxiliary contacts 23, and by conductor 88 to line L². As aforementioned segment 69 65 is arranged in circumferentially offset and non-overlapping relationship to segment 64 to insure against closure of switch 20 pending lapse of a short but predetermined period of time after closure of switch 19. Closure of the contacts 32 of 70 switch 20 results, as aforementioned, in exclusion of resistance 16 by a connection shunting both of the resistances 15 and 16, whereby the armature of motor M is connected directly across lines L¹, L². Thereafter winding 33 will be sufficiently 75

energized, by a circuit extending through contact 34, segments 57 and 58, contact 35 and resistance 82, to hold switch 20 closed pending disengagement of segment 58 from segment 35.

5 By reason of the continuous operation of pilot motor 7 it is to be understood that drum D may be in any angular or rotary position at the instant the contacts 52 are closed by closure of the tub door 8. If the left-hand side of drum D happens 10 to be in cooperative relationship to the contacts 34 to 39, whichever one of the group of segments 42 to 46 first engages contact 36 will cause closing energization of the operating winding of forward switch 17, and said switch will be maintained 15 closed pending such movement of drum D as will effect disengagement of segment 41 from contact 35. Prior engagement of one of the group of segments 41 to 51 with its cooperating contact 38 or engagement of one of the group of segments 53 to 56 with its cooperating contact 39 will 20 have no controlling effect upon the windings 31 and 33 of accelerating switches 19 and 20, due to the electrical interlock provided by the aforementioned auxiliary contacts 23 of switch 17. Also, as 25 aforescribed, the provision of auxiliary contacts 30 on switch 19 insures against closure of switch 20 prior to closure of switch 19. The segments at the right-hand side of drum D cooperate in a like manner with the respective contacts to insure 30 closure of switches 18, 19, and 20 in the desired sequence.

As will be apparent to those skilled in the art, the number of accelerating resistances 15, 16 may be increased or decreased if desired, with a corresponding change in the number of accelerating switches and drum segments and contacts for controlling the same. Inasmuch as the switch 19 must be closed as a prerequisite to closure of switch 20, it is obvious that the contacts 32 of the latter may be arranged to provide for short-circuiting of resistance section 16 only, instead of the particular arrangement herein illustrated.

By the means aforescribed I am enabled to insure substantially instantaneous starting of 45 motor M by merely closing the tub door 8, the inclusion of starting resistances 15, 16 in the motor circuit being insured, and proper acceleration of the motor by sequential exclusion of said resistances 15, 16 within a predetermined relatively 50 short period of time being likewise insured under all conditions.

In practice it is preferred to operate the drum D at a speed of between one and one-eighth and two and one-half revolutions per minute. The 55 importance and advantages of the system of control herein described are therefore apparent, inasmuch as the same insures a multiplicity of accelerating points around the drum, wherefore only a relatively short period of slow speed operation of the driving motor is required upon starting thereof, regardless of the angular position of the control drum at the instant of starting. Also as will be apparent from the foregoing description while the multiplicity of accelerating points are 60 individually effective during starting of the motor in each instance, those points not required to be utilized are automatically rendered temporarily ineffective for controlling the operation of the driving motor.

If the door of cylinder 7 is not properly registered with the opening in tub 6 at the time when the cylinder is brought to rest, it is obvious that further movement of the cylinder at slow speed 70 may be effected by temporarily closing tub door 75 8, whereby the tub door switch is utilized for

effecting inching of motor M. In practice, however, it may be desirable to provide a normally open push button switch (not shown), shunting the contacts 52 of the tub door switch, to provide for inching control of motor M while the tub door 5 8 remains in open position.

The modified form of control drum D¹ shown in Fig. 2 performs exactly the same functions as the drum D shown in Fig. 1 and may be substituted therefor if desired. Drum D¹ preferably 10 has a circumference equal to that of drum D. Also as will be noted drum D¹ may be substantially shorter, axially, than drum D. Certain of the parts employed in constructing drum D may be utilized in producing drum D¹, and corresponding parts are given like numerals of reference in the two figures. Thus I have shown in Fig. 2 the contact fingers 34, 35, 36, 38, and 39 which are adapted to cooperate with drum segments 40 to 51 and 53 to 56 identical with those 20 shown at the left-hand side of drum D in Fig. 1.

The contact finger 37 in Fig. 2 is circumferentially aligned with and diametrically opposed to contact finger 36, wherefore the segments 42 to 46 of Fig. 2 additionally serve to perform the functions of the segments 59 to 63 at the right-hand side of drum D in Fig. 1. Circumferentially aligned with and diametrically opposed to contact fingers 34, 35, 38, and 39 in Fig. 2 are a corresponding number of contact fingers 34^a, 35^a, 38^a, 39^a, which are respectively electrically connected with the former. As will be understood, the segments 40 to 51 and 53 to 56 occupy substantially one-half of the circumferential area of drum D¹, the other half of the drum circumference being free from segments. The arrangement is such that after the segments 40 to 51 and 53 to 56 have moved out of cooperative engagement with fingers 34 to 36, 38 and 39, the same will, in a like manner, cooperatively engage the contact fingers 34^a, 35^a, 37, 38^a, and 39^a, respectively, to perform control functions identical with those performed by the segments 57 to 72 at the right-hand side of drum D in Fig. 1. The contact fingers of drum D¹ are electrically 45 connected to the various control elements in the same manner as in the fingers of drum D in Fig. 1, as indicated by the several conductors 84, 85, 94, 90, and 93. The resistances 79 to 82 in Fig. 2 are identical with those shown in Fig. 1. 50

From the foregoing it will be seen that the drum D¹ in Fig. 2 requires only one-half as many segments as (or sixteen less than) the drum D in Fig. 1, whereas only four more contact fingers are required for drum D¹ than are required for 55 drum D. The advantages of the arrangement illustrated in Fig. 2 will therefore be apparent to those skilled in the art. The operation of drum D¹ and the functions performed thereby are believed to be obvious from the detailed description 60 of the device illustrated in Fig. 1.

What I claim as new and desire to secure by Letters Patent is:

1. The combination with an electric motor, of a device to be rotatably driven thereby, a pair of 65 electromagnetically operable switches adapted to be energized selectively to provide for forward or reverse operation of said motor, resistance to be included in circuit with said motor upon energization and closure of either of said switches, 70 at least one electromagnetically operable switch to be energized for effecting exclusion of said resistance, means to insure against energization and closure of said last mentioned switch prior to energization and closure of one of said switches 75.

- first mentioned, and means for initiating operation of said motor in one direction or the other within a relatively short period of time and for timing the operation of said resistance-excluding 5 switch, said means comprising a manually operable switch associated with said driven device and a continuously operable unidirectionally rotatable pilot drum, said drum having cooperating contacts and segments to provide for periodic 10 reversal of said motor and to provide for operation of said resistance-excluding switch within a predetermined relatively short period of time after completion of the circuit for the motor regardless of the instantaneous direction of operation 15 of the latter.
2. In a control system for motor driven washing machines and the like, the combination with a rotatable container, of an electric driving motor therefor, a pair of normally open electro- 20 magnetically operable switches adapted when closed selectively to provide forward and reverse circuit connections respectively for said motor, starting resistance to be included in circuit with said motor upon closure of either of said 25 switches, means comprising a normally open electromagnetically operable switch adapted when closed to effect exclusion of said resistance from the motor circuit, means comprising an electrical interlock to insure energization and 30 closure of one of said first mentioned switches prior to energization and closure of said last mentioned switch, a unidirectionally operable drum, a continuously operable pilot motor having a driving connection with said drum, said drum 35 having cooperating contacts and segments adapted when rendered effective to provide for energization and closure of one of said first mentioned switches within a predetermined relatively short period of time regardless of the instantaneous rotary position of said drum, associated 40 means to provide for maintaining said one of said switches closed pending a given operation of said drum to effect reversal of the motor circuit connections, and a switch associated with said rotatable container, said last mentioned switch being 45 manually operable to render said drum contacts and segments effective or ineffective at will to provide for completion or interruption of the motor circuit connections.
- 50 3. In a control system for motor driven washing machines and the like, the combination with a rotatable container, of an electric driving motor therefor, a pair of normally open electromagnetically operable switches adapted when closed 55 selectively to provide forward and reverse circuit connections respectively for said motor, starting resistance to be included in circuit with said motor upon closure of either of said switches, means comprising a normally open electromag- 60 netically operable switch adapted when closed to effect exclusion of said resistance from the motor circuit, means comprising an electrical interlock to insure energization and closure of one of said first mentioned switches prior to energization 65 and closure of said last mentioned switch, a unidirectionally operable drum, a continuously operable pilot motor having a driving connection with said drum, said drum having cooperating contacts and segments adapted when rendered 70 effective to provide for energization and closure of one of said first mentioned switches within a predetermined relatively short period of time regardless of the instantaneous rotary position of said drum, said drum contacts and segments also 75 cooperating under the last mentioned conditions
- to provide for energization and closure of said resistance-excluding switch within a predetermined relatively short period of time after energization and closure of said one of said first mentioned switches, associated means to provide for 5 maintaining said one of said switches and said resistance-excluding switch closed pending a given operation of said drum to effect reversal of the motor circuit connections, and a manually operable switch associated with said rotatable 10 container, said last mentioned switch being operable to render said drum contacts and segments effective or ineffective at will to provide for completion or interruption of the motor circuit 15 connections.
4. The combination with an electric motor, of a device to be rotatably driven thereby, a pair of electromagnetically operable switches adapted to be energized selectively to provide for forward or reverse operation of said motor, resistance to be 20 included in circuit with said motor upon energization and closure of either of said switches, a third electromagnetically operable switch to be energized for effecting exclusion of said resistance, means including sets of normally open 25 auxiliary contacts carried by the respective switches first mentioned, said auxiliary contacts being adapted to insure against energization and closure of said last mentioned switch prior to energization and closure of one of said switches 30 first mentioned, means for initiating operation of said motor in one direction or the other and for timing the operation of said resistance-excluding switch, said means comprising a manually operable switch associated with said driven device 35 and a continuously operable unidirectionally rotatable pilot drum, said drum having a group of equally spaced circumferentially aligned segments, a contact adapted when engaged by any one of said segments to effect energization and closure 40 of one of said first mentioned switches subject to prior closure of said manually operable switch, a second group of equally spaced circumferentially aligned segments axially spaced from said first mentioned group, and a contact adapted 45 when engaged by any one of said last mentioned segments to effect energization and closure of said resistance-excluding switch subject to prior closure of said one of said first mentioned switches, the segments of said second group being circumferentially offset relatively to the respective segments of the group first mentioned to thereby provide for lapse of a predetermined period of time between closure of said one of said first mentioned switches and said resistance-excluding switch. 50
5. The combination with an electric motor, of a device to be rotatably driven thereby, a pair of electromagnetically operable switches adapted 60 to be energized selectively to provide for forward or reverse operation of said motor, resistance to be included in circuit with said motor upon energization and closure of either of said switches, a third electromagnetically operable switch to be energized for effecting exclusion of said resistance, means including sets of normally open auxiliary contacts carried by the respective switches first mentioned, said auxiliary contacts being adapted to insure against energization and closure of said last mentioned switch prior to 65 energization and closure of one of said switches first mentioned, means for initiating operation of said motor in one direction or the other and for timing the operation of said resistance-excluding switch, said means comprising a manually oper- 70
- 75

able switch associated with said driven device and a continuously operable unidirectionally rotatable pilot drum, said drum having a group of equally spaced circumferentially alined segments, a contact adapted when engaged by any one of said segments to effect energization and closure of one of said first mentioned switches subject to prior closure of said manually operable switch, a second group of equally spaced circumferentially alined segments axially spaced from said first mentioned group, a contact adapted when engaged by any one of said last mentioned segments to effect energization and closure of said resistance-excluding switch subject to prior closure of said one of said first mentioned switches, the segments of said second group being circumferentially offset relatively to the respective segments of the group first mentioned to thereby provide for lapse of a predetermined period of time between closure of said one of said first mentioned switches and said resistance-excluding switch, said drum also having a third group of equally spaced segments circumferentially alined with each other and opposed to and axially offset from the group of segments first mentioned, and a contact adapted when engaged by any one of said last mentioned segments to effect energization and closure of the other of said first mentioned switches under the conditions aforesaid.

6. The combination with an electric motor, of a device to be rotatably driven thereby, a pair of electromagnetically operable switches adapted to be energized selectively to provide for forward or reverse operation of said motor, resistance to be included in circuit with said motor upon energization and closure of either of said switches, a third electromagnetically operable switch to be energized for effecting exclusion of said resistance, means including sets of normally open auxiliary contacts carried by the respective switches first mentioned, said auxiliary contacts being adapted to insure against energization and closure of said last mentioned switch prior to energization and closure of one of said switches first mentioned, means for initiating operation of said motor in one direction or the other and for timing the operation of said resistance-excluding switch, said means comprising a manually operable switch associated with said driven device and a continuously operable unidirectionally rotatable pilot drum, said drum having a group of equally spaced circumferentially alined segments, a contact adapted when engaged by any one of said segments to effect energization and closure of one of said first mentioned switches subject to prior closure of said manually operable switch, a second group of equally spaced circumferentially alined segments axially spaced from said first mentioned group, a contact adapted when engaged by any one of said last mentioned segments to effect energization and closure of said resistance-excluding switch subject to prior closure of said one of said first mentioned switches, the segments of said second group being circumferentially offset relatively to the respective segments of the group first mentioned to thereby provide for lapse of a predetermined period of time between closure of said one of said first mentioned switches and said resistance-excluding switch, said drum also having a third group of equally spaced segments circumferentially alined with each other and opposed to and axially offset from the group of segments first mentioned, a contact adapted when engaged

by any one of said last mentioned segments to effect energization and closure of the other of said first mentioned switches under the conditions aforesaid, and said drum also having a fourth group of equally spaced segments circumferentially alined with the segments of said second group and cooperating with the contact associated with the latter to likewise effect energization and closure of said resistance-excluding switch subject to prior closure of the other of said switches first mentioned.

7. As an article of manufacture, a pilot control drum including a multiplicity of segments all of which are electrically connected with each other, said segments comprising two pairs of relatively long segments of substantially equal dimensions, the segments of each pair being vertically spaced from and alined with each other and said pairs being arranged in slightly spaced and endwise alined relationship to each other circumferentially of the drum, two groups of directional switch controlling segments, the segments of each group being relatively small and the same being arranged in equally spaced relationship to each other within the circumferential limits of the pairs of segments first mentioned, said two groups of segments being arranged in offset relationship axially of the drum, two groups of accelerating switch controlling segments arranged in alinement circumferentially of the drum, the segments of each group last mentioned also being relatively small and the same being arranged in equally spaced relationship to each other within the circumferential limits of the pairs of segments first mentioned, and the segments of said last mentioned groups being arranged in circumferentially offset and non-overlapping relationship to the segments of the respective groups first mentioned, for the purpose set forth.

8. In combination, a pilot control drum including a multiplicity of segments all of which are electrically connected with each other, said segments comprising two pairs of relatively long segments of substantially equal dimensions, the segments of each pair being vertically spaced from and alined with each other and said pairs being arranged in slightly spaced and endwise alined relationship to each other circumferentially of the drum, two groups of directional switch controlling segments, the segments of each group being relatively small and the same being arranged in equally spaced relationship to each other within the circumferential limits of the respective pairs of segments first mentioned, said two groups of segments being arranged in offset relationship axially of the drum, two groups of accelerating switch controlling segments arranged in alinement with each other circumferentially of the drum, the segments of each group last mentioned also being relatively small and the same being arranged in equally spaced relationship to each other within the circumferential limits of the respective pairs of segments aforementioned, the segments of said last mentioned groups being arranged in circumferentially offset and non-overlapping relationship to the segments of the respective groups first mentioned, a pair of normally open electromagnetically operable directional switches and a normally open electromagnetically operable resistance-excluding switch, a plurality of contacts adapted for cooperation with said drum segments, one of said contacts being connected with a suitable source of energy supply, said contact being sequentially engageable by one of the seg-

- ments of each of said pairs, another of said contacts being connected through a corresponding number of current-limiting resistances with the operating windings of the directional switches and said resistance-excluding switch respectively, said last mentioned contact being sequentially engageable by the other of the segments of each of said pairs, said resistances being calibrated to permit only sufficient energization of the operating windings of the respective switches to maintain the latter closed after full energization of the respective windings, any one of the segments of one of the two groups first mentioned being cooperable with another of said contacts to effect short-circuiting of one of said resistances to provide for full energization of the winding of one of said directional switches, any one of the segments of the other of the two groups first mentioned being cooperable with another of said contacts to effect short-circuiting of another of said resistances to provide for full energization of the winding of the other directional switch, and any one of said two groups of accelerating switch controlling segments being cooperable with another of said contacts to effect short-circuiting of another of said resistances under predetermined conditions to provide for full energization of the winding of said resistance-excluding switch.
9. In combination, a pilot control drum including a multiplicity of segments all of which are electrically connected with each other, said segments comprising two pairs of relatively long segments of substantially equal dimensions, the segments of each pair being vertically spaced from and aligned with each other and said pairs being arranged in slightly spaced and endwise aligned relationship to each other circumferentially of the drum, two groups of directional switch controlling segments, the segments of each group being relatively small and the same being arranged in equally spaced relationship to each other within the circumferential limits of the respective pairs of segments first mentioned, said two groups of segments being arranged in offset relationship axially of the drum, two groups of accelerating switch controlling segments arranged in alignment with each other circumferentially of the drum, the segments of each group last mentioned also being relatively small and the same being arranged in equally spaced relationship to each other within the circumferential limits of the respective pairs of segments aforementioned, the individual segments of said last mentioned groups being arranged in circumferentially offset and non-overlapping relationship to the segments of the respective groups first mentioned, a pair of normally open electromagnetically operable directional switches and a normally open electromagnetically operable resistance-excluding switch, means comprising a set of normally open auxiliary contacts associated with each of said directional switches and requiring energization and closure of one of the latter as a pre-requisite to closing energization of said resistance-excluding switch, a plurality of contacts adapted for cooperation with said drum segments, one of said contacts being connected with a suitable source of energy supply, said contact being sequentially engageable by one of the segments of each of said pairs, another of said contacts being connected through a corresponding number of current-limiting resistances with the operating windings of the directional switches and said resistance-excluding switch respectively, said last mentioned contact being sequentially engageable by the other of the segments of each of said pairs, said resistances being calibrated to permit only sufficient energization of the operating windings of the respective switches to maintain the latter closed after full energization of the respective windings, any one of the segments of one of the two groups first mentioned being cooperable with another of said contacts to effect short-circuiting of one of said resistances to provide for full energization of the winding of one of said directional switches, any one of the segments of the other of the two groups first mentioned being cooperable with another of said contacts to effect short-circuiting of another of said resistances to provide for full energization of the winding of the other directional switch, any one of said two groups of accelerating switch controlling segments being cooperable with another of said contacts to effect short-circuiting of another of said resistances, subject to prior energization and closure of one of said directional switches, to provide for full energization of the winding of said resistance-excluding switch, and a single manually controlled switch operable to render said drum contacts and segments effective or ineffective at will.
10. In a control system of the character described, in combination, a rotatable device, an electric motor having a driving connection with said device, a pair of normally open electromagnetically operable switches one of which is adapted upon closure thereof to effect operation of said motor in one direction and the other of which is adapted upon closure thereof to effect operation of said motor in the reverse direction, resistance to be included in circuit with said motor upon closure of either of said switches, a third electromagnetically operable switch adapted upon closure thereof to effect short-circuiting of said resistance whereby said motor is accelerated, means for insuring against closure of said third switch pending closure of one of said pair of switches first mentioned, means comprising a continuously operable unidirectionally rotatable drum, said drum being normally operable to effect energization and closure of said pair of switches alternately for predetermined periods of time and to time the energization and closure of said third switch with respect to each of said pair of switches, each of said switches having a current-limiting resistance associated with the operating winding thereof and said drum having contacts and segments so arranged as to provide for intermittent short-circuiting of said resistances selectively, whereby said motor may be started in one direction or the other and accelerated within a predetermined relatively short period of time regardless of the instantaneous rotary position of said drum, and a single manually operable switch associated with said rotatable device and operable to render said drum effective or ineffective at will for controlling said electromagnetically operable switches.
11. The combination with a reversible electric driving motor, of control means therefor comprising a pair of electromagnetically operable reversing switches and a pair of electromagnetically operable accelerating switches, a pair of resistance sections to be included in circuit with said motor upon closure of either of said reversing switches, means to insure against energization of one of said accelerating switches pending closure of one or the other of said reversing

switches, said means comprising a set of normally open auxiliary contacts carried by each of said reversing switches, said auxiliary contacts being connected in parallel relation with each other in series with the operating winding of said accelerating switch, means to insure against energization of the other of said accelerating switches pending closure of said accelerating switch first mentioned, said means comprising a set of normally open auxiliary contacts carried by said accelerating switch first mentioned, said auxiliary contacts being connected in series with the operating winding of said second mentioned accelerating switch, a control drum adapted to rotate continuously in one direction, a single manually operable switch adapted when closed to render said drum effective, said drum having cooperating contacts and segments adapted to provide for energization and closure of one or the other of said reversing switches within a predetermined relatively short period of time regardless of the instantaneous rotary position of said drum, said drum also having cooperating contacts and segments to provide for energization and closure of said accelerating switches in a predetermined timed relation to each other within a predetermined relatively short period of time after closure of said reversing switches respectively, and current limiting resistances respectively interposed between one of said drum contacts and the operating windings of each of said reversing and accelerating switches to initially prevent closing of said reversing switches while providing for maintenance thereof in closed position throughout a predetermined cycle upon temporary short-circuiting of the respective resistances last mentioned through the medium of other of said drum contacts and segments.

12. The combination with a reversible electric driving motor, of control means therefor comprising a pair of electromagnetically operable reversing switches and a pair of electromagnetically operable accelerating switches, a pair of resistance sections to be included in circuit with said motor upon closure of either of said reversing switches, means to insure against energization of one of said accelerating switches pending closure of one or the other of said reversing switches, said means comprising a set of normally open auxiliary contacts carried by each of said reversing switches, said auxiliary contacts being connected in parallel relation with each other in series with the operating winding of said accelerating switch, means to insure against energization of the other of said accelerating switches pending closure of said accelerating switch first mentioned, said means comprising a set of normally open auxiliary contacts carried by said accelerating switch first mentioned, said auxiliary contacts being connected in series with the operating winding of said second mentioned accelerating switch, a control drum adapted to rotate continuously in one direction, a single manually operable switch adapted when closed to render said drum effective, said drum having cooperating contacts and segments adapted to provide for energization and closure of one or the other of said reversing switches within a predetermined relatively short period of time regardless of the instantaneous rotary position of said drum, said drum also having cooperating contacts and segments to provide for energization and closure of said accelerating switches in a predetermined timed relation to each other within a predetermined relatively short period of time after closure of said reversing switches within a predetermined relatively short period of time after closure of said accelerating switch first mentioned.

sure of said reversing switches respectively, current-limiting resistances respectively interposed between one of said drum contacts and the operating windings of each of said reversing and accelerating switches to initially prevent closing of said reversing switches while providing for maintenance thereof in closed position throughout a predetermined cycle upon temporary short-circuiting of the respective resistances last mentioned through the medium of other of said drum contacts and segments, said drum contacts and segments also acting to periodically effect reversal and acceleration of said motor in the manner aforescribed, and said manually operable switch being adapted when opened to render said control drum ineffective, whereby said motor may be stopped at will.

13. In a control system of the character described, in combination, a rotatable device, an electric motor having a driving connection with said device, a pair of normally open electromagnetically operable reversing switches and a pair of normally open electromagnetically operable accelerating switches for effecting control of said motor, control means for said switches comprising a manually operable switch associated with said rotatable device and a continuously operable unidirectionally rotatable drum, means operable independently of said drum to insure against closure of one of said accelerating switches prior to closure of one or the other of said reversing switches, means also operable independently of said drum to insure against closure of the other of said accelerating switches prior to closure of said accelerating switch first mentioned, said drum having cooperating contacts and segments so arranged as to provide for energization and closure of one or the other of said reversing switches within a predetermined relatively short period of time regardless of the instantaneous rotary position of said drum, and said contacts and segments also acting thereafter to effect sequential energization and closure of said accelerating switches within a predetermined relatively short period of time, whereby the period of slow speed operation of said motor upon starting thereof in either direction is minimized.

14. In a control system of the character described, in combination, a rotatable device, an electric motor having a driving connection with said device, a pair of normally open electromagnetically operable reversing switches and a pair of normally open electromagnetically operable accelerating switches for effecting control of said motor, control means for said switches comprising a manually operable switch associated with said rotatable device and a continuously operable unidirectionally rotatable drum, means operable independently of said drum to insure against closure of one of said accelerating switches prior to closure of one or the other of said reversing switches, means also operable independently of said drum to insure against closure of the other of said accelerating switches prior to closure of said accelerating switch first mentioned, said drum having cooperating contacts and segments so arranged as to provide for energization and closure of one or the other of said reversing switches within a predetermined relatively short period of time regardless of the instantaneous rotary position of said drum, and said contacts and segments also acting thereafter to effect sequential energization and closure of said accelerating switches within a predetermined relatively short period of time.

- period of time, whereby the period of slow speed operation of said motor upon starting thereof in either direction is minimized, and means associated with said drum contacts and segments
- 5 and said electromagnetically operable switches and adapted upon closure of one or the other of said reversing switches and said accelerating switches to normally maintain the same closed pending operation of the drum to one of a number
- 10 of predetermined rotary positions preparatory to reversal of the motor circuit connections.
15. In a control system of the character described, in combination, a rotatable device, an electric motor having a driving connection with
- 15 said device, a pair of normally open electromagnetically operable reversing switches and a pair of normally open electromagnetically operable accelerating switches for effecting control of said motor, control means for said switches comprising
- 20 a manually operable switch associated with said rotatable device and a continuously operable unidirectionally rotatable drum, means operable independently of said drum to insure against closure of one of said accelerating switches prior to
- 25 closure of one or the other of said reversing switches, means also operable independently of said drum to insure against closure of the other of said accelerating switches prior to closure of said accelerating switch first mentioned, said
- 30 drum having cooperating contacts and segments so arranged as to provide for energization and closure of one or the other of said reversing switches within a predetermined relatively short period of time regardless of the instantaneous
- 35 rotary position of said drum, said contacts and segments also acting thereafter to effect sequential energization and closure of said accelerating switches within a predetermined relatively short period of time, whereby the period of slow speed
- 40 operation of said motor upon starting thereof in either direction is minimized, means associated with said drum contacts and segments and said electromagnetically operable switches and adapted upon closure of one or the other of said re-
- 45 versing switches and said accelerating switches to normally maintain the same closed pending operation of the drum to one of a number of predetermined rotary positions preparatory to reversal of the motor circuit connections, said last
- 50 mentioned means comprising a corresponding number of current-limiting resistances interposed between the operating windings of the respective electromagnetically operable switches and one of said drum contacts, and means in-
- 55 cluding other of the drum contacts and segments for temporarily effecting short-circuiting of said resistances in a predetermined order.

16. As an article of manufacture, a pilot control drum including a multiplicity of segments all of which are electrically connected with each other, said segments comprising a pair of relatively long segments of substantially equal dimensions, the segments of said pair being vertically spaced from and aligned with each other, a group of directional switch controlling segments, the segments of said group being relatively small and the same being arranged in equally spaced relationship to each other within the circumferential limits of said pair of segments, two groups of accelerating switch controlling segments, the segments of each group last mentioned also being relatively small and the same being arranged in equally spaced relationship to each other within the circumferential limits of said pair of segments, and the segments of one of said last mentioned groups being arranged in circumferentially offset and non-overlapping relationship to the segments of the other of said last mentioned groups and to the segments of the group first mentioned, for the purpose set forth.

17. As an article of manufacture, a pilot control drum including a multiplicity of segments all of which are electrically connected with each other, said segments comprising a pair of relatively long segments of substantially equal dimensions, the segments of said pair being vertically spaced from and aligned with each other, a group of directional switch controlling segments, the segments of said group being relatively small and the same being arranged in equally spaced relationship to each other within the circumferential limits of said pair of segments, two groups of accelerating switch controlling segments, the segments of each group last mentioned also being relatively small and the same being arranged in equally spaced relationship to each other within the circumferential limits of said pair of segments, the segments of one of said last mentioned groups being arranged in circumferentially offset and non-overlapping relationship to the segments of the other of said last mentioned groups and to the segments of the group first mentioned, for the purpose set forth, five pairs of contact fingers, the contact fingers of each pair being diametrically opposed to each other and said pairs being circumferentially aligned with said relatively long segments and with said groups of segments respectively, the pair of contact fingers associated with said group of directional switch controlling segments having electrical connections individual thereto respectively, and the contacts of each of said other pairs being electrically connected with each other.

RALPH G. LOCKETT.
